UNITED STATES PATENT OFFICE

149,599

DESIGN FOR A CANDLESTICK

William H. Wilson, Hempstead, N. Y., assignor to
Wilson Industries, Inc., West Hempstead, N. Y.,
a corporation of New York

Application April 12, 1946, Serial No. 128,547

Term of patent 3½ years

(Cl. D48—2)

To all whom it may concern:

Be it known that I, William H. Wilson, a citizen of the United States and a resident of Hempstead, in the county of Nassau and State of New York, have invented a new, original, and ornamental Design for a Candlestick, of which the following is a specification, reference being had to the accompanying drawing, forming a part thereof.

Figure 1 is a plan view of a candlestick showing my new design; and

Figure 2 is a side elevation of said candlestick showing my new design.

I claim:

The ornamental design for a candlestick, as shown.

WILLIAM H. WILSON.
